UNITED STATES PATENT OFFICE.

SAMUEL CRAWFORD, OF LONDON, CANADA.

IMPROVEMENT IN HARVESTERS.

Specification forming part of Letters Patent No. 126,932, dated May 21, 1872.

Specification describing certain Improvements in Reaping-Machines for Harvesting Grain, invented by SAMUEL CRAWFORD, of the city of London, in the Province of Ontario and Dominion of Canada.

The object of my invention is to provide a convenient method of elevating and adjusting the grain-tables of reapers to the desired elevation.

Figure I is a side elevation embodying my invention. Fig. II is a plan of the same, showing the manner in which the sliding knuckle B is fitted to the table-bracket A.

The table-bracket A is bolted securely to the table T, and is so constructed that the knuckle-plate B may slide on it freely upward and downward. The rack C is formed on the edge of the knuckle-plate B. P is a lever, on one end of which is formed the segment D, having cogs, which work into the corresponding cogs of the rack C. E is a rack-bar, having notches to receive the latch with which the lever P is furnished, and in connection with which it is intended to hold the lever in its position as adjusted. I prefer making the table-bracket A to extend back to the point F, for convenience in adjusting the pivot or fulcrum F to the proper distance from the rack C. The arm G and grain-wheel H are constructed and arranged and work in the ordinary manner.

The front of the machine is indicated by the direction of the arrow.

To lower the grain-table T, I disengage the latch L from the rack-bar E and press the lever P downward. The knuckle-plate B is thereby forced upward on the table-bracket A and the grain-table T lowered correspondingly. To elevate the grain-table, I disengage the lever, as above described, and press it upward. The knuckle-plate B is thus forced downward on the table-bracket A and the table T elevated correspondingly, the rack-bar E always holding the apparatus as adjusted.

I claim—

As an improved device for raising and lowering the outer end of the platform in reaping-machines, the combination of the plate B, formed with a rack, C, upon its rear edge, sliding on a guide-flange on the bracket A, and carrying the grain-wheel H; the lever P, formed with a segment, D, gearing with the rack C, and fulcrumed upon the bracket A at a point, F, in rear of the sliding plate B; and the rack-bar E for securing the lever P in any position; the said parts being constructed and arranged to operate in the manner herein set forth.

Witnesses: SAMUEL CRAWFORD.

M. J. MC LAUCHLIN,
R. BANKS BARBER.
